UNITED STATES PATENT OFFICE

1,994,724

CONCRETE REINFORCEMENT SUPPORT

Roy M. Neely, Wilkinsburg, Pa., assignor to The American Steel and Wire Company of New Jersey, a corporation of New Jersey

Application January 20, 1932, Serial No. 587,821

1 Claim. (Cl. 94—8)

This invention relates to concrete road reenforcement positioning devices and particularly to those intended for use where the supporting surface is rather soft or sandy. One of the objects is to provide a device of the above character which may be cheaply made and which will maintain a vertical position when installed. Other objects will be made apparent by the following disclosure.

10 Having reference to the accompanying drawing:

Figure 1 is a side elevation of one form of the invention;

Figure 2 is an end elevation;

15 Figure 3 shows the appearance of the invention when installed;

Figure 4 shows a modification of the invention in side elevation;

20 Figure 5 is an end elevation of this modification; and

Figure 6 shows the same when installed.

In detail the invention consists of a support 1 having a pointed end 2 for reception by a road bed. A stop 3 is fixed at a predetermined point 25 to the support 1, this stop having sufficient length and being right angularly secured whereby the support is held vertically regardless of the road bed's condition. It is to be noted that the support 1 and the stop 3 comprise a pair of elongated bars cut from the same stock. A pair of reenforcement bars 4 is fixed to the support above this stop at points determined by the desired spacing of the road reenforcement. These bars are straight and are of such length as to permit 30 a reenforcement mat to be laid thereon at any one of a plurality of horizontally differing positions, as is shown particularly well by Figure 1, and are of a gage and ductility permitting their manual distortion about the reenforcement if desired. As it is necessary to use only two gages of rod it is possible to manufacture the device rather 35 cheaply.

A modification shown by the last three figures is substantially the same in principle as the device just described. The support 3, however, com-

prises a plurality of bars of similar gage to the support 1 that are built to provide a platform. In extremely sandy or loose soil this platform will more certainly insure vertical positioning of the support than will the single bar previously described.

The invention is particularly useful when a road reenforcement of the mat type is to be positioned. The construction of such a reenforcement makes it necessary to install all of the 10 supports prior to its application to the latter, instead of permitting their installation one at a time as is possible when a single bar constitutes a reenforcement. Therefore, the use of supports having receiving apertures or depressions requiring exact registration is almost an impossibility, it being very difficult to exactly predetermine the 15 positions of the supports with sufficient accuracy to meet the requirements of a mat. When using the new supports, it is only necessary to very 20 roughly position them, lay the mat on their reenforcement bars in a more or less haphazard manner and to then bend these bars around the mat wherever possible.

Although I have shown and described a specific 25 form of my invention in accordance with the patent statutes, I do not intend to limit myself thereby except as defined by the appended claim.

I claim:

A positioning device for concrete road reenforcements of the mat type, including the combination of a relatively long bar constructed for insertion into the ground and with sufficient rigidity to support such a reenforcement, a stop fixed to said bar so as to limit its insertion into the 30 ground, and at least one reenforcement carrying 35 bar right angularly immovably fixed to the first named bar, the second named bar being straight and of such length as to permit a reenforcement mat to be laid thereon at any one of a plurality of 40 horizontally differing positions and being of such gage and ductility as to permit it to be manually bent around the contacting portion of the same.
